US0D1061509S

(12) **United States Design Patent** (10) **Patent No.:** **US D1,061,509 S**
(45) **Date of Patent:** **** Feb. 11, 2025**

(54) **COMPUTER**

(71) Applicant: **Siemens Aktiengesellschaft**, Munich (DE)

(72) Inventors: **Joachim Hirth**, Karlsruhe (DE); **Tobias Reese**, Gundelsheim (DE); **Nina Wendt**, Bayern (DE)

(73) Assignee: **Siemens Aktiengesellschaft**, Munich (DE)

(**) Term: **15 Years**

(21) Appl. No.: **29/839,363**

(22) Filed: **May 20, 2022**

(30) **Foreign Application Priority Data**

Nov. 22, 2021 (EM) 008768758

(57) **CLAIM**

The ornamental design for a computer, as shown and described.

DESCRIPTION

FIG. 1 is a front elevational view of a computer showing our new design;

FIG. 2 is a rear elevational view thereof;

FIG. 3 is a top plan view thereof;

FIG. 4 is a bottom plan view thereof;

FIG. 5 is a right-side elevational view thereof;

FIG. 6 is a left-side elevational view thereof; and,

FIG. 7 is a front, top and right-side perspective view thereof. The broken lines in the drawings illustrate portions of the computer that form no part of the claimed design.

1 Claim, 7 Drawing Sheets
